(57) **CLAIM**

The ornamental design for a docking station, as shown and described.

DESCRIPTION

FIG. 1 is a front perspective view of a docking station showing the new design shown in an open position; FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view of the docking station of FIGS. 1-7 shown in a closed position;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken line showing of the various elements of the docking station in the figures is for environmental purposes only and forms no part of the claimed design. FIGS. 1-7 show the docking station in a first positional state and FIGS. 8-14 show the docking station in a second positional state. FIGS. 1-7 in combination with FIGS. 8-14 show a docking station in two positional states.

1 Claim, 12 Drawing Sheets
